(57) CLAIM

The ornamental design for a luminaire, as shown and described.

DESCRIPTION

FIG. 1 is a top isometric view of an embodiment of a luminaire.

FIG. 2 is a bottom isometric view of the luminaire of FIG. 1.

FIG. 3 is a front elevation view of the luminaire of FIG. 1.

FIG. 4 is a back elevation view of the luminaire of FIG. 1.

FIG. 5 is a right side elevation view of the luminaire of FIG. 1, the left side elevation view being a mirror image of the right side view.

FIG. 6 is a top plan view of the luminaire of FIG. 1; and, FIG. 7 is a bottom plan view of the luminaire of FIG. 1.

Portions or features of the luminaire not shown in the drawings form no part of the claimed design. The broken lines in the drawings form no part of the claimed design.
